Application June 29, 1935, Serial No. 57,463

Term of patent 7 years

To all whom it may concern:

I, Ray J. D'Aschbach, a citizen of the United States, residing at Van Nuys, in the county of Los Angeles, State of California, have invented a new, original, and ornamental Design for a Decorative Pompon or Similar Article, of which the following is a specification, reference being had to the accompanying drawing, forming a part thereof.

The figure is a perspective view of the decorative pompon or similar article, showing my new design.

The decorative article comprises hollow, tubu-

lar and translucent elements of various lengths, arranged in such manner that said tubular elements appear to radiate from a common point, thereby creating an effect of a decorative pompon, a representation of a cluster of pine needles, or the like.

I claim:

The ornamental design for a decorative pompon or similar article, substantially as shown and described.

Signed at Los Angeles, California, this 24th day of June, 1935.

RAY J. D'ASCHBACH.
